UNITED STATES PATENT OFFICE.

WILLIAM C. McKEOWN, OF BUFFALO, NEW YORK, ASSIGNOR TO BUFFALO RADIATOR COMPANY, OF BUFFALO, NEW YORK, A CORPORATION OF NEW YORK.

DESIGN FOR A RADIATOR.

No. 38,676.

Specification for Design.

Patented July 9, 1907.

Application filed May 23, 1907. Serial No. 375,361. Term of patent 14 years.

To all whom it may concern:

Be it known that I, WILLIAM C. McKEOWN, a citizen of the United States, residing at Buffalo, in the county of Erie and State of New York, have invented a new, original, and ornamental Design for Radiators, of which the following is a specification, reference being had to the accompanying drawing, forming part thereof.

The figure is an end view of the radiator, showing my new design.

I claim,—

The ornamental design for a radiator, as shown.

WILLIAM C. McKEOWN.
